C. R. RANEY.

AUXILIARY BUFFER FOR SHOCKERS.
APPLICATION FILED DEC. 19, 1917.

1,328,795.

Patented Jan. 20, 1920.

UNITED STATES PATENT OFFICE.

CLEMMA R. RANEY, OF CHICAGO, ILLINOIS, ASSIGNOR, BY MESNE ASSIGNMENTS, TO INTERNATIONAL HARVESTER COMPANY, A CORPORATION OF NEW JERSEY.

AUXILIARY BUFFER FOR SHOCKERS.

1,328,795.

Specification of Letters Patent. Patented Jan. 20, 1920.

Application filed December 19, 1917. Serial No. 207,863.

To all whom it may concern:

Be it known that I, CLEMMA R. RANEY, a citizen of the United States, residing at Chicago, in the county of Cook and State of Illinois, have invented certain new and useful Improvements in Auxiliary Buffers for Shockers, of which the following is a full, clear, and exact specification.

This invention relates to grain shockers, and more particularly to tripping mechanism for throwing into operation the delivery fork which delivers the sheaves to the shock receptacle. The invention has been illustrated in connection with the Raney type of shocker, such as shown in Patent No. 1,222,798, Raney, April 17, 1917. In this type of machine the releasing means for the delivery fork comprises a rock shaft positioned at one side of the fork, and having 20 upstanding tines which are so located as to be engaged by the sheaf as it is discharged from the binder deck. When the sheaves engage these tines the shaft is rocked, and by means of a suitable clutch the sheaf delivery fork is thrown into operation. Although 25 provision has been made in this shocker for stopping the discharging mechanism of the binder while the sheaf delivery fork of the shocker is operating, instances have occurred 30 in which the discharging mechanism of the binder has discharged sheaves when the sheaf delivery fork of the shocker was not in position to receive them. When a sheaf has been discharged from the binder, and 35 the delivery fork is not in position to receive it the rock shaft is rotated and is sometimes held in its rotated position, and as the delivery fork returns to sheaf receiving position another sheaf will be discharged, and 40 will rotate the rock shaft still farther. This continued rotation has occasioned the breaking or twisting of the rock shaft, thereby putting the machine out of operation.

With the above noted difficulties in mind 45 I have devised my present invention in which provision is made for taking up these unusual strains on the rock shaft or trip shaft, thereby avoiding the breakage of the shaft.

50 In the drawings I have illustrated one embodiment of my invention, and

Figure 1 shows a plan view of the front portion of a Raney shocker;

Fig. 2 is a side elevation, partly in sec-

tion, of my improved rock shaft construction;

Fig. 3 is a section on line 3—3 of Fig. 2 looking in the direction of the arrows; and

Figs. 4 and 5 are detail views on an enlarged scale showing the connection between the trip shaft and the clutch controlling member 36.

The front portion of the shock receptacle 10 is supported through the usual braces 11 on the transversely extending supporting member 12 secured to the frame of the binder, and extending outwardly beneath the binder deck. The sheaf delivery fork 13 is carried by a shaft 14, operated by driving mechanism 15, and controlled by a clutch 16. This driving mechanism and clutch are fully illustrated in my prior patents, and attention is directed to Patent No. 1,222,798 above referred to.

The trip shaft 17 is journaled at one end 75 in suitable journaling means disposed on the under side of the supporting member 12, and at the other end is connected to the frame of the shocker in a manner hereinafter described. This trip shaft carries on its rear 80 end a sleeve 18, which is rotatably mounted on the shaft, and is held against longitudinal movement by the cotter pin 19. This sleeve is provided with an outwardly extending offset portion 20, having a projection 21 85 on the outer end thereof through which extends a link 22. This link 22 carries a spring 23 on its outer end, and a nut 24 for adjusting the tension of the spring. The inner end of the link 22 is pivotally connected to an outwardly projecting extension 24' formed integral with a clamp 25, which is secured to the trip shaft 17. The link 22 is screw threaded and is provided with a nut 22', as illustrated in Figs. 2 and 3 for 90 adjusting the relative positions of the extensions 20 and 24'.

From the above description it will be seen that the rocking motion of the trip shaft 17 is communicated through the clamp 25, link 100 22 and sleeve 18 to the outwardly extending bifurcated portion 26 of said sleeve. The bifurcated portion 26 forms one portion of a hinged connection, the other portion of which is embodied in the outwardly extending bifurcated portion 27 of a casting 28 105 pivotally secured to the frame of the shocker. This casting is pivoted on a stub shaft 29

carried by the shocker frame, and has formed integrally therewith an upwardly and outwardly extending projection 30 which is screw threaded at its upper end to receive a 5 screw threaded pin 31. This pin may be adjusted in the screw threaded aperture in the casting, and acts as a stop to limit the outward rotational movement of the rock shaft 17 by engaging the frame 10 of the 10 shocker. The casting 28 also carries an inwardly extending projection 32, the end of which is pivoted to a link 33, which extends across the front of the shocker frame, and carries at its opposite end the rear end of a 15 rod 34, which extends forwardly, and its forward end is bent upwardly to a position on the binder deck where it is engaged by the sheaves as they pass from the discharging mechanism into the binder. This construction is fully illustrated in the patent 20 above referred to, and has therefore not been shown in detail in this application.

The casting 28 also carries at its rear end an outwardly projecting clamp 35, in which 25 is carried an upwardly extending locking member 36, which is bent inwardly at its rear end, as shown at 37, to form a dog which controls the operation of the clutch 16, thereby controlling the operation of the 30 sheaf delivery fork. The rock shaft 17 is provided with upwardly extending sheaf guiding tines 38, which are engaged by the sheaves as they are discharged from the binder deck. The position of the tines 38 and rock shaft 17 can be controlled by 35 means of the adjustment of the nut 22' on the link 22. The tines and the rock shaft are first inserted in the clamp 25 in the approximate position of adjustment, but by 40 changing the position of the nut 22' and causing the extensions 20 and 24' to move relative to each other, a finer adjustment may be obtained.

The operation of the device is as follows: When the sheaf is discharged from 45 the binder deck it engages the tines 38, thereby rocking the shaft 17, the sleeve 18, casting 28 and pawl 37, and releasing the sheaf delivery fork 13. The tines 38 also 50 perform the function of arresting or stopping the sheaves after they are discharged from the binder deck, and of guiding the sheaves on to the sheaf delivery fork 13. If the rock shaft 17 is in its normal position 55 when engaged by the sheaf there will be substantially no relative rotation between the rock shaft and the sleeve 18, but should the shaft be disposed in such a position that the tines 38 are inclined rearwardly when a 60 sheaf is discharged from the binder deck, and engages these tines in which position the pin 31 engages frame 10, the shaft 17 will be rotated, and through the clamp 25, link 22 and spring 23 the rotation of the 65 shaft will be communicated to the sleeve 18,

the spring taking up the excess rotation of the shaft. The point of rotation of shaft 17 in which the adjustable pin 31 engages the frame 10, therefore determines the point of operation of the resilient connection between the shaft 17 and sleeve 18. In this way the excess rotation will do no damage and the shaft will not be broken under the unusual strain put upon it. 70

While I have in the above specification 75 described one embodiment which my invention may assume, it will be understood that the invention is capable of many modifications, and that such modifications may be made without departing from the spirit 80 of the invention as expressed by the following claims.

What I claim as new is:

1. In a shocker, a frame, sheaf delivery means, means for operating said delivery means, and mechanism carried by and supported entirely on said frame for controlling said operating means, said controlling mechanism having means for taking up excessive strains on said controlling mechanism. 85

2. In a shocker, sheaf delivery means, actuating means therefor, including a clutch, clutch controlling means including a locking member mounted on a horizontal 95 pivot, a rock shaft disposed in substantial alignment with said pivot and resilient connecting means interposed between said locking member and said rock shaft.

3. In a shocker, a sheaf delivery member, 100 operating means therefor, controlling mechanism for said operating means including a member located adjacent said sheaf delivery member and having sheaf guiding means located in the path of the sheaves deposited 105 on said delivery member, said controlling member having means for taking up excessive strains thereon.

4. In a shocker, sheaf delivery means, actuating means therefor, including a clutch, 110 clutch controlling means including a locking member mounted on a horizontal pivot, a rock shaft disposed in substantial alignment with said pivot, resilient connecting means between said locking member and 115 said rock shaft, and means for simultaneously adjusting the tension of said resilient connecting means and the relative positions of said locking member and said rock shaft.

5. In a shocker, a sheaf delivery member, 120 actuating means therefor including a clutch, clutch controlling means comprising a rotatable member, a second member journaled on said first named member and rotatable with respect thereto, and resilient means for 125 controlling the relative rotation of said members.

6. In a shocker, a sheaf delivery member, actuating means therefor including a clutch, and controlling means for said clutch com- 130

- prising a rock shaft, and a sleeve journaled on said rock shaft and rotatable with respect thereto, and resilient means carried by said rock shaft and operatively connected 5 with said sleeve whereby the rotated movement of said rock shaft is communicated to said sleeve.
7. In a shocker, a sheaf delivery means, actuating means therefor including a clutch, 10 a rock shaft, a sleeve journaled on said rock shaft, resilient means carried by said rock shaft and operatively connected with said sleeve whereby the movement of said rock shaft is communicated to said sleeve, and a 15 dog for controlling said clutch operatively connected to said sleeve.
8. In a shocker, sheaf delivery means, actuating means therefor including a clutch, a rock shaft, a clamp secured to said rock 20 shaft, a link pivoted on said clamp, a sleeve journaled on said rock shaft and resiliently connected to said link, and a dog operatively connected to said sleeve for controlling said clutch.
- 25 9. In a shocker, a frame, sheaf delivery means, means for operating said delivery means, and oscillatory controlling mechanism for said operating means, said mechanism being carried by and supported entirely on said shocker frame, said mechanism having means for taking up strains due to the oscillation of said mechanism through an excessive degree of movement.
- 30 10. In a shocker, a sheaf delivery member, means for operating said member, a controlling member for said operating means, said controlling member having a sheaf guiding portion thereof located in the path of the sheaves after said sheaves are discharged from the binder and as they are 40 deposited on said delivery member and being movable by said sheaves to release said operating means, and means for taking up excessive movement of said controlling member. 45
11. In a shocker, sheaf delivery means, means for operating said sheaf delivery means, a controlling member for said operating means, and means resiliently connected to said member and having sheaf guiding means located in a position to be engaged by the sheaves as they are being deposited on said delivery means. 50
12. In a shocker, a sheaf delivery member, means for actuating said sheaf delivery member, controlling means for said actuating means, resilient connections between said actuating means and said controlling means, and adjustable means for determining the point of operation of said resilient 55 connections. 60
13. In a shocker, a sheaf delivery member, means for actuating said delivery member, controlling means for said actuating means, resilient connections between said actuating means and said controlling means, and adjustable means carried by said controlling means for determining the point of 65 operation of said resilient connections. 70
14. In a shocker, a sheaf delivery member, actuating means therefor; controlling means for said actuating means, a sheaf guiding member positioned adjacent said delivery member, and resilient connections between said sheaf guiding member and said controlling means. 75

In testimony whereof I affix my signature.
CLEMMA R. RANEY.
